(57) **CLAIM**

The ornamental design for a screen cover for a general purpose engine as shown and described.

DESCRIPTION

FIG. 1 is a front elevational view of a screen cover for a general purpose engine showing our new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof;

FIG. 7 is a front and left perspective view thereof;

FIG. 8 is a rear and right perspective view thereof; and,

FIG. 9 is a perspective view of the screen cover, shown in position of use.

The broken lines in FIGS. 1 to 9, showing portions of a screen cover for a general purpose engine, form no part of the claimed design.
